(57) **CLAIM**

(21) Appl. No.: **29/372,259**

The ornamental design for clip on tool holder for gripping on to a garment, as shown and described.

(22) Filed: **Nov. 1, 2010**

DESCRIPTION

(51) **LOC (9) Cl.** 03-01

FIG. 1 is a perspective view of a clip on tool holder for gripping on to a garment showing my new design;

(52) **U.S. Cl.** D3/228

FIG. 2 is a top plan view thereof taken in the direction of arrow 2 in FIG. 1;

(58) **Field of Classification Search** D3/228,

FIG. 3 is a front elevational view thereof taken in the direction of arrow 3 in FIG. 1;

D3/215, 224; 206/372-379; 224/268-269,
224/247-248, 234, 666-669, 673, 677-678,
224/904; D8/373; 24/3.1, 3.2, 3.11-3.12

FIG. 4 is a right side elevational view thereof taken in the direction of arrow 4 in FIG. 1, it being understood that the left side is a mirror image thereof;

See application file for complete search history.

FIG. 5 is a rear elevational view thereof taken in the direction of arrow 5 in FIG. 1;

(56) **References Cited**

FIG. 6 is a bottom plan view thereof taken in the direction of arrow 6 in FIG. 1;
